greenhouse construction, and more particularly to a construction in which the wall members are extended upwardly and curved inwardly to merge with the roof. The curved extensions of the wall members are glazed so that they form in effect a lower continuation of the roof.

Greenhouses have heretofore been constructed of two general classes, namely, with the roof formed of planes with their lower edges resting directly on the walls, and with the lower edges of the roof curved. In the second type it has heretofore been thought necessary to construct the roof substantially entirely of steel and glass. This construction, however, not only added expense but increased the amount of shadow in the interior of the greenhouse.

In cases where the lower edges of the roof were curved it was thought necessary to use the steel construction in order to give sufficient rigidity to the roof itself.

The principal feature of this invention is to provide a structure which is the equivalent of a roof with its lower edges curved and yet construct a roof itself substantially entirely of wood and glass. I accomplish this by extending the walls upwardly and curving them inwardly. The upwardly extending curved extensions of the walls, however, are glazed to such an extent that they admit sufficient light so that they outwardly appear as portions of the roof itself. These upwardly extending curved extensions are suitably braced and rigid and stiff enough, however, so that they virtually form integral parts of the side walls. With this construction there may be supported on the upward edges an ordinary roof with two planes and such roof may be made principally of wood and glass.

It is thus possible to produce a greenhouse having substantially all the optical advantages of the older type of construction with a curved roof and at the same time have the structural simplicity and inexpensiveness of a wood and glass roof. This is accomplished, as stated, by extending the rigid side walls upwardly and inwardly in a curve, glazing the upwardly curved extensions and supporting a wood roof upon the upper edges of the curved extensions.

Other features and advantages will appear more fully as I proceed with my specification.

In that form of device embodying the features of my invention shown in the accompanying drawings—Fig. 1 is a view in vertical cross-section; Fig. 2 is a similar view on an enlarged scale showing the upwardly extending curved

extension of one of the side walls; Fig. 3 is a view in side elevation taken at right angles to Fig. 2; and Fig. 4 is a view in perspective of one of the reinforcing members used in the side wall extension.

As shown in the drawings, the greenhouse includes suitable foundations 11 for the side walls. The side wall comprises a base 13 which may be made of concrete, brick, or the like, on which are supported suitable posts 14 which may have 10 window frames 15 between them.

Each of the posts 14 carries an upwardly extending inwardly curved rigid cast metal member 50, the lower end of which carries a plate 28 provided with holes 51, 51 by which it may be securely bolted to the upper end of the post 14. At the top of the plate 28 there is provided a flat horizontal plate 52 adapted to rest on the top of the post 14 to give it additional rigidity and security.

The member 50 is preferably in the form of a T in cross-section with the flange 22 on the outer curved surface and the web 23 on the inner side. The upper end of the member 50 carries a perforated plate 24 to which the longitudinal angle iron 25 may be attached to secure the upper ends of the members 50, 50 together.

The spaces between the curved members 50 may be glazed, for example, by the provision of curved wooden members 26 fastened to the members 50 carrying glass 53 between them.

It will be seen that by the construction above described, the vertical side walls are extended upwardly substantially to the extremities of the curved members 50, such upwardly extending extensions of the side walls being curved inwardly. Since the members 50 are relatively narrow, the panes of glass 53 are large enough so that these extensions will outwardly appear as lower continuations of the roof. As a matter of fact, however, the members 50 are strong and rigid and form integral parts of the side walls so that the construction is really one in which the side walls are extended upwardly and curved inwardly. The members 50 act as stiffening members for the extensions of the side walls so that the roof can be supported by the upper edges of said wall extensions. Consequently the roof may be formed principally of wooden joists 16 with their lower ends carried by the upper ends of the members 50. Between the members 16 is provided the ordinary roof glazing 54.

The lower ends of the members 16 meet the upper ends of the members 26 and are both fastened to plates 27 carried at the upper ends of 55

the curved members 50, so that, to all outward appearances, the roof construction is extended downwardly to the lower ends of the members 50, making it appear as if the roof itself had its lower edge curved.

Near its lower end the member 50 is provided with a plate 31 upon which the angle iron 32 may be mounted to serve as a water shed member over the sash 55 mounted in the frame 15.

10 Near the lower end of the member 50 is also provided a V shaped notch 56 adapted to support a drip conductor 35.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. In a greenhouse construction: a rigid side wall; a plurality of upwardly extending inwardly curved, metallic members on said side wall; a purlin connecting the ends of the metallic members; a wooden joist extending from the end of

each curved member to the ridge and supporting the glass of the roof, said wooden joists being free from any continuous support, and wooden members mounted upon said metallic members supporting a glass side wall extension, each of said wooden members being flush at one end with a joist to provide an unbroken line from ridge to side wall, and whereby the support for the roof glass and the support for the side wall extension glass form a continuous unbroken line.

2. A greenhouse construction as set forth in claim 1 in which the wooden joists are provided with a central support independent of the metallic members.

3. A greenhouse construction as set forth in claim 1 in which the purlin abuts directly against the ends of the curved metallic members.

4. In a greenhouse construction an upwardly extending, inwardly curved metallic member provided with an outwardly extending flange at a lower portion thereof, the flange having a shoulder on its upper surface to support a curved wooden glass supporting member, means upon the flange for securing the metallic member to a side wall, and said flange being recessed to provide a support for a drip trough within the greenhouse.
